UNITED STATES PATENT OFFICE.

PAUL MEYELIN, OF PANTIN, FRANCE.

SHAVING BRUSH.

Application filed September 12, 1924. Serial No. 737,379.

To all whom it may concern:

Be it known that I, PAUL MEYELIN, a citizen of the French Republic, and resident of 54 Rue Cartier Bresson, Pantin, Seine, France, have invented certain new and useful Improvements in Shaving Brushes, of which the following is a specification.

Shaving brushes of the ordinary description for spreading soap over or lathering the 10 face, preparatory to shaving, comprise a sleeve and a bunch of animal or vegetable fibres or bristles; these two parts forming a permanent whole.

The utilization of these shaving brushes 15 by private persons, shaving themselves, is not open to objection, or attended with danger. On the other hand, however, shaving brushes used by barbers, are open to the serious drawback that they are employed 20 for everybody, and as it frequently happens that the skin becomes scraped off or scratched by the razor, there is the danger of serious infectious diseases being transmitted from one person to another.

25 The object of the present invention is to obviate this danger by providing a shaving brush, in the case of which the fibrous or bristle portion can be renewed for each customer.

30 The brush constructed according to the invention comprises essentially a sleeve or holder portion and a brush portion in the strict sense of the term. The sleeve or equivalent part, which is of any suitable 35 material, is provided with means for holding or releasing, in a simple and easy manner, the brush portion proper.

The brush portion may be made from natural fibres or bristles, such as badger hair, 40 textile or other material, to suit requirements.

The brush portion is by preference previously treated with a soap solution and then dried, so that it is only necessary to use plain 45 water at the time of shaving.

A safety band or the like may be stuck over the bristle portion. This may constitute a cap or pocket which wholly or partially covers the bristles, and which is so attached that it is necessary to tear or break it when the brush portion is to be used.

The accompanying drawing shows, by way of example, one constructional embodiment of the invention, but it is to be understood 55 that any other forms or constructional em-

bodiments depending upon the same principle are included in the invention.

In the drawings:—

Fig. 1 is a sectional elevation of the handle portion of the device. 60

Fig. 2 is a bottom plan, with the fastening means in the disengaged position.

Fig. 3 is a part sectional view of the removable ring or holder.

Fig. 4 is a corresponding plan. 65

Fig. 5 is a perspective view illustrating the method of assembling the device.

1 is a handle of any suitable material adapted to fit into the ring portion of the bristle holder 2, by which the bristles 3 70 are carried.

7 is a bar carried by a rod 5 rotatable in a longitudinal hole in the handle 1. It is held in position by a screw 4, the inner end of which screws into a hole in the rod 5. 75 The body of the screw 4 passes through an elongated slot 4', which enables the rod 5 to be rotated about its axis through a short distance. 8 are diametrically opposite grooves or notches at the bottom of the handle, which in one position of the bar 7 are clear of the ends thereof, as shown at Fig. 2, whilst in another position the ends of the bar 7 come over or beneath the notches for the purpose hereinafter explained. 6 is a spring which is so arranged 80 that it tends normally to bring the bar 7 into the position with the ends thereof over or below the notches 8.

The upper portion 10 of the ring or holder 2 is provided with inwardly extending portions 9, which are of a size adapted to fit 85 into the grooves or notches 8, but which extend downwards only for a short distance, so that a lower step or edge 11 is formed as shown at Fig. 3.

The top of the bristle portion 3 is provided with a flattened surface indicated by 12, Fig. 3.

The method of utilizing the device will 100 be easily understood. The holder portion 2 may be supplied, with the bristles in position, and the holder, which is of cheap construction thrown away after each time of using; or the holder may be retained 105 and the bristle portion before removal of the safety cap be inserted on each occasion.

To place the holder in position, the bar 7 is turned out of the way of the grooves 8 by pressing upon the screw 4 as indicated 110

at Figs. 2 and 5. The ring of the holder is pushed into position with the projections 9 entering the grooves or notches 8, and when the parts have been pushed home the screw 4 is released and under the influence of the spring 6 the bar 7 turns so that its opposite ends lodge between the parts 11 and 12, thus holding the bristle portion in position.

10 What I claim and desire to secure by Letters Patent of the United States of America is:—

15 In a shaving brush, the combination of a handle provided with a longitudinal hole, a spindle rotatable in the said hole and provided with a bar extending across the bottom of the said handle, means for rotating the said spindle through a small arc,

grooves at the edge of the handle adapted to be covered by the ends of the bar in one 20 position and to be uncovered in another position thereof, a spring adapted to turn the bar into the position where the grooves are covered, a cap like holder adapted to fit over the bottom of the handle and furnished with a brush proper, the said holder being provided with inwardly projecting portions adapted to slide into the grooves in the bottom of the handle and so formed that the bar carried by the handle is adapted to engage them under the influence of the spring, substantially as and for the purposes set forth.

In witness whereof I affix my signature.

PAUL MEYELIN.
